UNITED STATES PATENT OFFICE

165,901

ELECTRIC CONDUIT SUPPORTING SPACER

Wallace M. Bloom, South Milwaukee, and Aldred J. Simmons, Plymouth, Wis., assignors to McGraw Electric Company, Milwaukee, Wis., a corporation of Delaware

Application August 28, 1950, Serial No. 11,968

Term of patent 14 years

(Cl. D26—9)

To all whom it may concern:

Be it known that we, Wallace M. Bloom and Aldred J. Simmons, citizens of the United States and residents, respectively, of South Milwaukee, in the county of Milwaukee and State of Wisconsin, and of Plymouth, in the county of Sheboygan and State of Wisconsin, have invented a new, original, and ornamental Design for Electric Conduit Supporting Spacer, of which the following is a specification, reference being had to the accompanying drawing, forming a part hereof.

Fig. 1 is a perspective view of an electric conduit supporting spacer, showing our new design; and

Fig. 2 is a side-elevational view thereof.

Both sides of the spacer are substantially identical.

We claim:

The ornamental design for an electric conduit supporting spacer, as shown and described.

WALLACE M. BLOOM.
ALDRED J. SIMMONS.
